UNITED STATES PATENT OFFICE.

EBBE J. HANSEN, OF LOS ANGELES, CALIFORNIA.

COMBINATION-TOOL.

1,329,707.

Specification of Letters Patent.

Patented Feb. 3, 1920.

Application filed January 7, 1918. Serial No. 210,647.

To all whom it may concern:

Be it known that I, EBBE J. HANSEN, a citizen of the United States, residing at Los Angeles, in the county of Los Angeles, State 5 of California, have invented new and useful Improvements in Combination-Tools, of which the following is a specification.

This invention has relation more specifically to that class of tools where a single 10 instrument is provided with a number of parts formed and combined together to produce a series of useful tools most commonly utilized by housewives and others in similar occupations.

An object of my invention is to provide an 15 instrument combining several useful household implements in a single unitary co-operating structure that shall be efficient and reliable as well as inexpensive considering the number of various tools embodied in a single structure.

With the above and other objects in view the invention consists in the details of construction, and in the arrangement of parts 25 to be hereinafter more fully set forth and specifically claimed.

This invention will be more readily understood by reference to the accompanying drawings forming a part of this specification, and in which:

Figure 1 is a side elevation.

Fig. 2 is an edge view.

Fig. 3 is an end elevation.

Fig. 4 is a cross sectional detail view of 30 one of the tool implements taken on line 4-4 of Fig. 1.

Referring more specifically to the drawings, the tool preferably consists of two movable members 5 and 6 secured together 40 by a pivot pin or rivet 7, one end of each of members 5 and 6 terminating in handles 8 and 9.

Preferably, these members are formed of sheet steel (as that material possesses great 45 strength and durability) struck from dies. The end of member 5 opposite its handle 8 is provided with can opening device preferably formed integrally therewith, consisting of a jaw 10 provided with a beveled cutting edge 11, its outer end terminating in a can 50 piercing point 12. To one side of jaw 10 extending parallel therewith, and spaced therefrom is an extension 13 provided with a depressed portion 14 forming a strengthening rib. The extreme outer end 15 of ex-

tension 13 is bent at substantially right angles and at an inclination to its body portion to form a jaw 16, one transverse edge of said jaw being toothed as at 17 to form a fulcrum when the tool is used as a can 60 opener, the opposite disposed transverse edge 18 being curved outwardly as clearly shown in the various figures of the drawing, to form one member 19 of a pan or pot lifting instrument, the other member 20 being 65 formed on one end of movable member 6 which will be more particularly described hereinafter.

Jaw 16 is provided with a depression 21 forming a strengthening rib, the vertically 70 disposed parallel side edges 22, 23 from approximately midway between the two transverse edges being inclined downwardly and toward each other and terminating in a blunt point 24 as clearly shown in Fig. 3 of 75 the drawing. By forming the end of jaw 16 opposite to toothed edge 17 of member 5 into a blunt point, I am enabled to quickly engage the edge or rim of a pan in which a pie or cake is being baked without injuring the crust or cake, the point being inserted between the cake and the inner surface of the pan rim.

The outer portion of extension 13 is bent 85 transversely and at an angle to its rear portion so that its longitudinal axis is in alignment with the longitudinal axis of the can cutting jaw 10, thus materially strengthening the extension when the instrument is used as a can opener.

The outer end of member 6 opposite its handle 9 is provided with an extension arm 25, the edge adjacent extension 13 being curved away therefrom. This outer curved edge of arm 25 is provided with a projection 95 preferably formed integrally therewith and bent at substantially right angles to arm 25 to form a clamping jaw 20 adapted to coöperate with its companion clamping jaw 16 to form a pan or cooking utensil 100 lifter. The face of jaw 20 is concaved as clearly shown in Figs. 2, 3, and 4 of the drawings for the reception of rib 21 formed on jaw 16 when the jaws are brought together, thus enabling the operator to maintain a firmer grip on a pan or other utensil 105 when the tool is used as a lifter.

Movable member 6 is provided on its outer edge and adjacent to the pivotal point 7 with a bottle opening hook 28 which may be uti- 110

lized in removing crimped caps from bottles, the outer edge 29 of jaw 10 acting as a fulcrum for the hook.

Referring more particularly to Figs. 1 5 and 2 of the drawings, a portion of the outer edges of members 5 and 6 adjacent the inner ends of handles 8 and 9 are bent at right angles thereto to form flanges 30, 31, segmental in form, the inner faces of said 10 flanges being toothed or serrated as at 32 to form gripping surfaces. Member 6 is further provided with a segmental flange 33, similar in all respects to flanges 30 and 31, said flange coöperating with the other 15 flanges when the handles 8 and 9 are brought together to form a circular jar top wrench. By means of the above described wrench tops of fruit jars can be readily removed when desired.

20 After the above description the operation of the various well known tools or implements will be perfectly apparent without the necessity of further explanation. It may be stated, however, in the way of point-

ing out the advantages of my combination 25 tool that such tool has been designed and constructed with a view to the attaining of the same results as the usual separate tools and to the proper balancing of the entire structure. Moreover, I have made the tool 30 easy and solid of grasp by the hand, so that it may be most efficient.

What I claim is:

A combination tool, comprising two members pivotally secured to each other, one of 35 said members having a can opener formed thereon, said can opener consisting of a cutting jaw and a fulcrum jaw disposed in parallel relation to each other, and the other of said members having a jaw formed thereon, the fulcrum jaw of the can opener coöperating with the jaw formed on the second 40 mentioned member to form a utensil lifter.

In witness that I claim the foregoing I have hereunto subscribed my name this 13th 45 day of December, 1917.

EBBE J. HANSEN.
